CLAIM

The ornamental design for a combined loudspeaker
cabinet, sound reflector and support base, as shown and
described.

DESCRIPTION

FIG. 1 is a front elevational view of a combined loudspeaker
cabinet, sound reflector and support base showing
my new design;

FIG. 2 is a rear elevational view thereof;

FIG. 3 is a right side elevational view thereof, the left
side being a mirror image;

FIG. 4 is a top plan view thereof; and

FIG. 5 is a bottom plan view thereof.
